**ELECTRICAL CONTACT WITH SCREW TERMINAL
AND PRESSURE-LOCK TERMINAL**
Ronald G. Munroe, Old Bridge, N.J., assignor to Eagle
Electric Mfg. Co., Inc., Long Island City, N.Y., a cor-
poration of New York
Filed June 1, 1965, Ser. No. 460,330
8 Claims. (Cl. 339—95)

This invention relates to an electrical contact which is combined with both a screw terminal and an integral pressure-lock.

Pressure-lock terminals have recently become popular for home electrical devices, particularly those which are designed for installation by a householder. This is quite understandable because they are extremely easy to connect in circuit, requiring simply stripping the insulation off the end of a conductor and thrusting the exposed tip of the metal core into an opening in the insulating housing for the electrical device. Typical pressure-lock terminals are disclosed in United States Letters Patent Nos. 2,705,785 dated Apr. 5, 1955, and 2,952,831 dated Sept. 13, 1960, it being understood that reference thereto is merely exemplificative and not restrictive. However, pressure-lock terminals do not invariably provide an acceptable or even desirable electrical connection.

Frequently electrical devices of the character described which include electrical terminals are installed behind a wall surface and in such a case it may be a violation of an electrical code to employ a pressure-lock terminal connection. It also may be considered undesirable because a settling of a house might exert sufficient pressure on such a connection to open it, in which event the bare core of the electrical wire would be exposed and be the possible cause of a hidden short circuit. Furthermore, under some conditions, it may be desirable in addition to connecting the wire system of a house to an electrical device, to make a further connection from such electrical device to a further electrical device, in other words, to effect a junction between two wires at an electrical device. Pressure-lock terminals are not constructed for the admission of two wires, nor do they in their present form lend themselves readily to modification for this purpose. On the other hand, a screw type terminal provides an arrangement that can itself, or with suitable modifications, be employed to effect a connection between two metal wire cores. Hence, there will be occasions when it is desirable to have a pressure-lock terminal available and other occasions when it would be useful to have an electrical screw terminal available.

The present conventional type of pressure-lock terminal does not lend itself to combination with a screw terminal. A pressure-lock terminal is characterized by the provision of a cantilever-mounted spring tongue having a tip arranged near, and at an angle to, a stationary anvil thereby provide a narrow gap into which the tip of the metal core of an electric conductor is thrust, the angle between the spring and the anvil on the side of the tongue at which the conductor is introduced being acute so that the conductor can easily cam its way into and through the gap but will be engaged by the tip of the tongue acting as a retrograde check or spur that digs into the wire conductor to prevent its accidental withdrawal.

It has been the practice in present-day pressure-lock terminals to make the cantilever tongue that is employed of light gauge spring stock inasmuch as the flexing action of the tongue must take place in cramped quarters and the tongue must not offer too much resistance to the introduction of a metal conductor. Thus, in a duplex electrical receptacle which is one popular site for pressure-lock terminals the pressure-lock tongue has its tip adjacent the bridge that connects the two electrical contacts

2

of the receptacle and the tongue is in one piece with such bridge so that it must experience an appreciable degree of angular movement for proper operation. Hence, it is particularly desirable that the tongue and bridge be of rather slight thickness in order to enable it to experience the requisite degree of flexing.

Due to the necessary lightness, that is to say, thin gauge of metal that must be used, to allow the tongue to flex under the foregoing circumstances, it has not been possible until now to combine a pressure-lock terminal with a screw terminal unless there additionally is employed a stiffening piece of metal, such for instance as a small steel plate, which is clamped or welded to the bridge between the contacts, which plate is sufficiently strong to be apertured and tapped for reception of the terminal screw. Although it is not structurally impractical to use the extra metal plate in order to accomplish the above described function, in a business where parts are made in extremely large quantities by mass production and where manufacturing costs are under retail pressure for low pricing, the addition of the extra plate and its attachment to the bridge is not looked upon with favor.

It is an object of the present invention to provide a combined pressure-lock and screw terminal which is not subject to the foregoing drawbacks.

It is another object of the invention to provide a combined pressure-lock and screw terminal in which the pressure-lock terminal and the means for threadably receiving the screw are unitary, i.e., of a single piece.

It is another object of the invention to provide a device of the character described constituting a combined unitary, that is to say, one piece, contact, pressure-lock terminal and support for a terminal screw.

It is another object of the invention to provide a device of the character described which is so designed that the pressure-lock terminal can be made of heavier stock than presently is employed so that the same stock can serve to provide a tapped opening for the reception of a terminal screw.

It is another object of the invention to provide a device of the character described which is so designed that the pressure-tongue is fashioned from what otherwise would be waste stock, so that the device can be made at a particularly low cost. In this latter connection it is observed that in a combined contact and pressure-lock terminal, such as heretofore has been conventional, the pressure-tongue was formed from an additional width of stock which therefore gave rise to considerable waste, the recovery value of which was negligible since it had to be sold for reclaiming as scrap. On the other hand, pursuant to the present invention, where the pressure-tongue is arranged to be blanked out of what otherwise would be scrap, an appreciable savings is effected.

It is another object of the invention to provide a device of the character described in which, despite the consolidation of the pressure-lock with a screw terminal, said lock nevertheless is efficient and effective in operation and will provide an attachment to a wire connector that is at least as firm as that presently effected by pressure-lock terminals of light gauge stock.

Other objects of the invention in part will be obvious and in part will be pointed out hereinafter.

The invention accordingly consists in the features of construction, combinations of elements and arrangement of parts which will be exemplified in the device hereinafter described and of which the scope of application will be indicated in the appended claims.

In the accompanying drawings in which is shown one of the various possible embodiments of the invention,

FIG. 1 is a top plan view of a duplex receptacle employing combined contacts, pressure-lock terminals and screw terminals in accordance with the present invention.

tion, said receptacle having one lateral half of its top housing removed to show a part of the interior of the receptacle with the associated combined contacts and terminals;

FIG. 2 is a cross-sectional view taken substantially along the line 2—2 of FIG. 1;

FIG. 3 is an enlarged fragmentary cross-sectional view taken substantially along the line 3—3 of FIG. 1 and illustrating the construction of the pressure-tongue, the cantilever-mounted base thereof and the anvil against which the pressure-tongue urges a bare metal conductor wire;

FIG. 4 is a perspective view of a combined unitary pair of contacts, pair of pressure-lock terminals, bridge and pair of mounts for terminal screws, a fragment of one of the mounts being broken away to expose for illustrative purposes the tip of one of the pressure-tongues;

FIG. 5 is a top plan view of a band of metal stock showing the outlines of successive blanks for devices of the present invention which will be cut out therefrom; and

FIG. 6 is a side view of the receptacle.

In general, the several objects of the present invention are achieved by making the pressure-lock and contact components of the instant device from comparatively heavy electrically conductive sheet metal stock rather than the light stock that has been employed heretofore for pressure-lock terminals and contacts, such previous stock having been too light to conveniently provide a tapped bore for reception of a screw terminal. Particularly good results have been accomplished where the stock of the combined one-piece contacts and terminals constitutes extra hard brass approximately three one-hundredths of an inch in thickness. This is a rather stiff stock. It is much too heavy for use in a present-day pressure-lock terminal of standard construction where it would render the pressure-tongue too stiff to be flexed by introduction of a standard bare conductor wire. However, such heavy stiff brass stock is conventionally employed at the present time for electrical contacts that do not have unitary pressure-lock terminals, i.e., for electrical contacts in general and for electrical contacts that have screw type terminals. Thus, the stock is sufficiently flexible, even though stiff, for use as an electrical contact component. The requisite additional flexibility, to wit: flexibility beyond that necessary for use as a contact, in order to employ this stock as a pressure-lock tongue, is obtained by spacing the cantilever-mounted base of the tongue a considerable distance from the anvil with which the tip of the tongue cooperates. Heretofore, as has been noted above, the anvil for the tongue conventionally has constituted the bridge which extended between a pair of contacts of a duplex receptacle. In accordance with the present invention, the anvil now constitutes a flange adjacent the contact which flange is spaced at the maximum practical distance from the cantilever-mounted base of the pressure-tongue. It has been found that within the dimensions prevailing in a duplex receptacle, such spacing imparts sufficient flexibility to the stiff brass stock to enable the pressure-tongue to function properly.

Referring now in detail to the drawings, the reference numeral 10 denotes a duplex bayonet plug receptacle which is a type of electrical device that can utilize the present invention to good advantage inasmuch as the housing of the device, save for its front face, is, in use, located behind a wall surface. Other electrical devices which also can efficaciously employ the present invention are, by way of example, single and triple bayonet plug receptacles, screw base receptacles and wall switches.

The duplex receptacle 10 includes a housing 12 of electrically non-conductive material, e.g., a thermo-setting plastic such as a phenol-formaldehyde condensation resin. The housing is composed of a top housing part 14 and a bottom housing part 16. These parts are molded to provide the usual conventional external shape and a suitable

substantially conventional internal shape which is proper to receive and support the contacts and terminals.

In particular, the top housing part 14 is formed with the customary pairs of bayonet-passing slots 18, two pairs of these slots being included because the device is a duplex receptacle. Also present in the duplex receptacle herein illustrated, but not as a part of the invention, are a pair of grounding slots 20. Thus the receptacle is designed to receive a plug, not shown, having a pair of parallel bayonet power prongs of flat blade-like configuration and a third bayonet grounding prong which may be of circular cross-section or of a cross-section in the form of a rectangle with one arcuate side.

The top housing part 14 is molded to include a central longitudinal separator 22 and the bottom housing part to include a central longitudinal separator 24, said separators being interengaged internally of the receptacle to subdivide the interior of the housing into two longitudinal compartments 26. A portion of each compartment extends into the bottom of the top housing part and the remainder into the top of the bottom housing part.

The separators 22, 24 are relieved for lightness and economy and also to accommodate a mounting strap 28 and a grounding strap (not shown). The ends of the grounding strap include downwardly extending legs which form grounding contacts 30, each of which is located slightly inwardly of a different grounding slot 20 so as to be engaged by a grounding prong inserted into the same. The grounding strap is made of a thin resilient electrically conductive metal such as phospho-bronze.

The mounting strap is conventional and comprises plated iron sheet metal shaped to the usual form having outwardly extending ends 32 configured for ready engagement to a structural element of a building or to a metal outlet box. The central portion of the mounting strap passes between the two separators 22, 24 and said strap is held in place by a metal rivet 34 that extends through registered holes in the strap and the top and bottom housing parts. The same rivet also extends through the grounding strap which is in face-to-face contact with the under surface of the mounting strap.

As is customary, the rivet is tapped for reception of a screw that is employed to hold the escutcheon plate for the receptacle. Thereby a grounding connection is provided from the grounding contacts through the rivet and mounting strap 28 to the outlet box which, in accordance with standard practice, is grounded.

Located in each of the compartments 26, is a different contact-terminal device 36 embodying the present invention. Since these devices are identical only one will be described.

Each device includes a body portion constituting two co-planar flat shanks 38 separated by a deep locating notch 40 which is adapted to engage a locating ridge 42, transversely disposed in and molded in one-piece with the bottom housing part 16 so as to insure proper lengthwise positioning of the contact-terminal device within the receptacle. The two shanks 38 are firmly tied together by a junction span 44 in the form of a flat nib which projects upwardly and outwardly away from the shanks 38 in order to clear the top housing part 14. The corners of the bottom edge of the nib are in one-piece with the adjacent upper inside corners of the shanks 38 and indeed all parts of the contact-terminal device are formed from a single piece of stock, this being the comparatively heavy electrically conductive extra-hard brass stock to which reference heretofore has been made.

The flat shanks 38 are of rectangular shape and are in lengthwise alignment. The two said shanks together with the junction span jointly form what will, upon occasion, hereinafter be referred to as a "contact-bridge" inasmuch as these three elements together constitute that part of the contact-terminal device which extends between, physically and electrically connects, and supports contacts at its ends. For reference purposes, the different

edges of each flat shank will be designated as follows: 38a the inner side edge, 38b the bottom edge, 38c the top edge and 38d the outer side edge.

In said duplex receptacle, each of the side walls 45 of the bottom housing part is formed with a closely positioned pair of broad deep through notches 46, each of which extends down from an open mouth at the top edge of the wall. The notches are separated by the locating ridge 42. The flat shanks 38 are disposed adjacent the inner face of the side wall 45 and thus are exposed to a substantial extent through the notches 46. The inner edges 38a of the shanks rest against the side surfaces of the locating ridge.

The thus exposed portion of each shank 38 is centrally apertured to provide an opening 48. Desirably the openings are initially formed to a smaller than required diameter, as by punching, and then subsequently are enlarged by a drawing pin which raises a squat annular flange on the inner surface of the shank. The opening 48 and the associated flange are tapped to receive a terminal screw 50. Thus, there are two such terminal screws on each side of the duplex receptacle, each affiliated pair of screws being engaged to a different contact-terminal device and being connected to a different side of the electric line. These screws may be employed to make an electrical connection from the house wiring system to the contact-bridges or they may be employed to effect an electrical connection between two house wires at the receptacle or they may be employed to effect an electrical connection from the receptacle to a house wire which supplies electrical energy to a different electrical device. It will be appreciated that in the foregoing manner a simple screw-terminal has been consolidated into the contact-terminal device 36. The screw-terminal is readily and easily accessible and does not interfere with either the contacts or the pressure-lock terminals soon to be described.

If desired, the tips of the screws 50 may be staked to prevent inadvertent withdrawal of the same from the tapped opening 48.

It will be observed (see FIG. 1) that the power-prong receiving slots 18 are spaced laterally inwardly from the side walls 45 of the bottom housing part. Since the effectively plane contact-bridge lies against the internal surface of the associated side wall of the receptacle and since the contact-bridge is in one-piece with the contacts, it is necessary to provide the contact-terminal device with laterally inwardly extending offset flange 52 at each end thereof, this being customary in the art, to align the contacts with the slots. Each flat shank 38 accordingly has an offset flange 52 formed in one-piece therewith at its outer side edge 38d. The flanges are perpendicular to the shanks and extend inwardly from the edges 38d, said flanges serving as intermediate conventional supports connecting the contact-bridge with contacts 54 at opposite ends of the device.

The contacts 54 may be of any desired structure which is such as to locate contact elements in operable positions below the associated power-prong passing slots 18. Thus each contact may consist of only a single contact blade or, as shown, it may consist of a pair of opposed contact blades, the latter being more customary because it provides a more certain and higher physical pressure engagement between the contact and a power prong. The particular contact structure illustrated is desirable because it enables a minimum width of band to be employed for blanking of the devices 36 therefrom; accordingly, its construction will be detailed.

The contact 54 includes two opposed blades, to wit: an outer blade 56 and an inner blade 58 (see FIG. 4). Said blades have substantial portions thereof mutually coextensive and are located behind an affiliated slot 18 so that a power prong will be in line with the zone between the blades. The outer blade 56 is parallel to the nearby side wall of the receptacle. The inner blade 58

may likewise be parallel thereto but preferably, and as shown, is tilted at a slight angle to the outer blade so that the outermost edges of the blades touch one another as shown in FIGS. 1 and 4, while the opposite edges of the blades are slightly spaced apart. The upper ends of the blades have angled lead-in tips 60 to cam an improperly introduced power prong into the zone between the blades. The outer blade 56 is connected by a right angled stub leg 62 to the edge of the offset flange 52. The inner blade 58 is connected by a longer acutely angled leg 64 to the edge of the offset flange. The two legs 62, 64 are respectively located at the upper and low regions of the inner edge of the offset flange, that is to say, the two legs are at different non-overlapping elevations on the contact-terminal device. To increase the resiliency of the mounting of the inner blade 58, the leg 64 is longer than necessary to place the inner blade in juxtaposition to the outer blade and the additional length is formed into a bight 66.

The usual dimple 68 is indented into the outer surface of the outer blade so as to raise a corresponding locking protuberance 70 on the inner face of said blade.

To aid in inhibiting longitudinal shifting of the contact-bridge, the two offset flanges 52 at the opposite ends of said bridge engage ribs 72, 73 formed internally of the bottom housing part 16.

As thus far described, it will be apparent that the contact-terminal device has the approximate shape of a very shallow U with out-turned tips at the ends of its legs. The base of the U constitutes the contact-bridge 30 which is composed of the pair of shanks 38 joined by the span 44, the legs of the U constitute the offset flanges 52 and the out-turned tips at the ends of legs constitute the contact structure 54. The resemblance of the device to a shallow U is of importance in considering the arrangement now to be described for the construction of pressure-lock terminals 74.

It already has been pointed out that a pressure-lock terminal essentially is composed of two elements, to wit: an anvil and a pressure-tongue. The anvil in the pressure-lock terminal 74 is the offset flange 52. The pressure-tongue is denoted by the reference numeral 76 and best can be seen in FIGS. 3 and 4.

The pressure-tongue is in the shape of an elongated narrow strip that is in one piece with the contact-terminal device and has a flat base 78 extending from that part of the bottom edge 38b of the affiliated flat shank 38 which is next to the inner edge 38a. Said base 78 is oriented perpendicular to the plane of the flat shank. Except for the base 78 the pressure-tongue is unconnected to the edge 38b so that it is free to flex. The pressure-tongue includes an arched portion 80 extending over approximately 120° and unitarily joined at one end to the base 78. Said arched portion extends downwards, away from the shank and then curls back toward the shank at its other end. From its said other end the arched portion tangentially runs into an intermediate reach 82 that lies at an angle of about 120° to the base 78 and crosses the bottom of the shank. The intermediate reach in turn supports a terminal reach 84 that lies at an angle of about 135° to the base so that said reach makes an angle of approximately 45° to the anvil 52.

The tip of the terminal reach is close to the offset flange (anvil) 52, the spacing therebetween being less than the diameter of the smallest bare conductor wire that will be used to make a connection to the receptacle. Preferably, the corner of the tip which faces the anvil is substantially square in order thereby to obtain an efficient pressure-locking effect.

The zone between the tip of the terminal reach and the anvil is spaced about midway between the upper and lower edges 38c, 38b of the shank and an opening 88 is formed in the bottom wall 86 of the bottom housing part 16 in registry with said zone to admit a bare conductor wire 90. As will be seen in FIG. 3, when said wire is thrust into the opening 88 it will be guided into the space be-

tween the terminal reach and the offset flange due to the angled inclination of the reach 84. The bare conductor wire will force the reach away from the anvil so as to permit the wire to be introduced into the zone between the anvil and the corner of the tip of the terminal reach. Once the bare conductor wire is emplaced, as shown in FIG. 3, any force tending to withdraw it will cause the pressure-tongue to dig into the wire so that the tongue acts on a retrograde checking pawl which prevents withdrawal of the wire.

An unlocking opening 92 is formed in the base wall 86 alongside the wire insertion opening 88 and in line with the intermediate reach 82 (see FIG. 3). When it is desired to release a wire held by the pressure-lock terminal, the tip of a slender rigid instrument, such as a screw driver, is inserted into the opening 92 and pressed against the intermediate reach, causing the terminal reach to flex away from the anvil and thereby releasing the wire 90 caught thereunder.

It will be observed that because of the substantial space which conventionally is provided between the center of a contact-bridge and an offset flange, the length of a pressure-tongue that extends over said space in a non-linear fashion, is sufficiently great to permit the tongue to flex readily when a bare conductor wire end is pressed against its terminus; this, despite the comparative heaviness and stiffness of the stock from which the contact-terminal device is fabricated and which are required for proper formation of a tapped opening to receive a threaded terminal screw. The non-linear configuration of the pressure-tongue between its base and its tip, and to which reference just has been made, results from both the arched portion 80 which extends first downwardly from the base and then back up toward the tip of the tongue and the location of the tip of the tongue high on the offset flange, e.g., between $\frac{1}{3}$ and $\frac{1}{2}$ of the height of the flange from the bottom edge 38b.

In order to accommodate said arched downwardly protruding portion, the bottom wall 186 of the bottom housing part is locally depressed beneath said portion to include a well 94 shown in FIG. 3, one edge of the well constituting an edge of the unlocking opening 92.

The low point of the arched portion is disposed close to the bottom surface of the well 94 and, preferably, will engage the same when idle. However the full length of the tongue, from its base to its tip, will flex when a wire is introduced.

Attention is directed to the fact that the unique structure and mounting of the pressure-tongue which enables it to cooperate with the offset flange as a pressure-lock has an additional advantage which is not apparent at first glance. This is that the pressure-tongue is constituted from that part of the original band stock which otherwise would be scrap, so that the pressure-lock tongue can be included in the device without increasing the width of band of sheet metal stock required, or the length along the stock for each device. To illustrate the foregoing, in FIG. 5 there is shown a short length of band stock with a series of successive contact-terminal devices laid out in the flat thereon. The parts of the blank have been numbered in the same fashion as the corresponding parts of the finished device except for the openings 96 which subsequently are enlarged and flanged to form the tapped openings 48. From inspection of FIG. 5 it will be seen that the lead-in tips of the contact blades protrude above the top edges 38c of the flat shanks 38 and that the space between these tips which in part includes the junction span 44 and which otherwise would be waste, is occupied by the pressure-tongues 74.

Also as seen in FIG. 5, the terminal reach 84 is somewhat narrower than the intermediate reach 82. Inasmuch as the intermediate reach is wider than the offset flange, the reduction in width matches the width of the terminal reach to that of the offset flange.

It thus will be seen that there is provided a device which achieves the several objects of this invention and which is well adapted to meet the conditions of practical use.

As various possible embodiments might be made of the above invention, and as various changes might be made in the embodiment set forth, it is to be understood that all matter herein described or shown in the accompanying drawings is to be interpreted as illustrative and not in a limiting sense.

Having thus described my invention I claim as new and desire to secure by Letters Patent:

1. In a combined contact and pressure-lock terminal, a shank having a bottom edge and a side edge, said edges being at right angles to one another, a flange on said side edge for connection with and support of a contact, said flange extending inwardly at right angles to said shank and constituting an anvil of a pressure-lock terminal, said terminal further including a pressure-tongue cooperating with said anvil, said pressure-tongue including a base 20 cantilever-connected to and extending inwardly from the bottom edge of the shank remotely from the said side edge and adjacent the opposite side edge, the entire length of said tongue, except the base, being free of the shank, the tip of said tongue being angled upwardly away from 25 the bottom edge of the shank to terminate close to but spaced from the flange a distance therefrom less than the diameter of a bare conductor wire, said pressure-tongue including an intermediate section between the base of the tongue and the tip thereof, said intermediate section extending from the base of the tongue downwardly away from the bottom edge of the shank and then reversing to 30 extend upwardly and cross the bottom edge of the shank, said shank, flange and pressure-tongue being formed of a single piece of heavy stiff electrically conductive sheet 35 metal stock.

2. A combination as set forth in claim 1 wherein the intermediate section includes an arched portion connected to the base and in excess of 90° and less than 180° in length, said arched portion terminating at the end thereof remote 40 from the base in an intermediate reach.

3. A combination as set forth in claim 2 wherein the intermediate reach is a tangential extension of the arched portion.

4. A combination as set forth in claim 1 wherein the 50 base of the pressure-tongue is perpendicular to the shank.

5. A combination as set forth in claim 4 wherein the base of the pressure-tongue is also perpendicular to the flange.

6. A combination as set forth in claim 1 wherein the 55 shank is rectangular.

7. A combination as set forth in claim 1 wherein means is included to define a tapped opening in the shank for reception of a terminal screw.

8. A combination as set forth in claim 1 wherein means 60 is included to define a tapped opening in the shank and wherein a terminal screw is engaged in said opening.
